POLISHING OR GRINDING ROLL

Henry H. Giles, Lincoln Place, Pa.; Dora Thompson Giles executrix of said Henry H. Giles, deceased

Application December 22, 1936, Serial No. 117,156

1 Claim. (Cl. 51—193)

This invention relates to the polishing or grinding of sheets to a high degree of luster, and more particularly to the rolls which are intended to perform this function.

5 It is among the objects of the present invention to provide a roll for polishing or grinding operations which does not produce irregularities in the surface of the work-piece; and one which does not require axial oscillation to avoid this in-

10 jurious condition.

Another object is to provide a roll of the class described which is characterized by a maximum depth of resiliency and also a practical compressive and elastic surface.

15 The foregoing and other objects will be apparent after referring to the drawing, in which:

Figure 1 is a plan of one form of apparatus of the invention.

Figure 2 is a side elevation of the apparatus of 20 Figure 1.

Figure 3 is an enlarged elevation of a detail.

Figure 4 is a sectional view on the line IV—IV of Figure 3.

Referring more particularly to the drawing, the 25 numeral 1 designates a table on which is supported a wheeled carriage 4 adapted to travel upon track members 4^a. The carriage 4 is adapted to be reciprocated on the table 1 between stops 2 and 3 by a fluid pressure cylinder 20 having

30 its piston-rod 21 connected to the carriage, as at 22. Fluid pressure may be admitted to the cylinder 20 at opposite ends for reciprocating the carriage 4 in any well known manner. It will be understood that any other suitable means for

35 reciprocating the carriage 4 may be substituted for the cylinder 20 and piston-rod 21. The stops 2 and 3 may be used to operate suitable control mechanism for reversing the carriage 4, if desired.

In the particular and preferred embodiment 40 shown, the carriage 4, with the substantially flat metallic sheet 5 to be polished, is adapted to be reciprocated under a polishing or grinding belt 6 which is trained about rollers 7 and 8.

The roller 7 is adapted to be power-driven by 45 any suitable means, such as the speed reducer 8^a and motor 24. The rollers 7 and 8 are journaled in suitable bearings in supports 7^b and 8^b, respectively, which extend upwardly from the table member 1.

50 The carriage 4 is provided along at least one edge with a pivoted clamping jaw 10 which, by means of an eccentric or cam 11, is made to engage and disengage one or more tabs 9, which are secured to the sheet 5 as, for instance, by welding. This construction and arrangement en-

ables the holding of the sheet 5 against movement on the carriage 4, and permits its entire surface to be uniformly polished.

The pressure rolls 7 may be used to support and drive a polishing or grinding belt, as shown at 6, or may be used as a direct contact polishing or grinding roll, as in both instances its construction and arrangement allows its novel advantages to function equally well. In either event this pressure roll 7 (Figure 3) is made up of a plurality of circular sections 12 which are centrally mounted in abutting relationship about a shaft 13, the latter being supported in bearings 13^a. Between each of the sections 12 and also encircling the shaft 13 are thin steel plates 14 which serve to structurally support the sections 12. These thin steel plates 14 are of less diameter than the outer diameter of the sections 12 so as not to contact at any time the flat metallic sheet 5 being polished or ground.

The circular sections 12 are laterally compressed and held thus by circular collared end plates 15 at each end of the assembled roll, the end plates 15 being secured to the shaft 13 in any convenient manner.

In order to positively prevent the rotation of the circular sections 12, they, the plates 14, and the end plates 15, may all be keyed to the central shaft 13, as shown at 13^b.

In order to facilitate readily securing the end plates 15 to the shaft 13, the extreme end circular sections 12 are wedge-shaped, as at 16, but are in all other respects identical with the other sections 12.

Heretofore, polishing or grinding rolls for the 35 purpose described have usually been made up of a plurality of stitched sections, each section of which was usually of circular buffing cloth of 18-ply canvas. These cloth sections were assembled on a central shaft so that their abutting surfaces 40 were at right angles thereto.

In order to increase the polishing or grinding effect, the roll was forced into closer contact with the work-piece by decreasing the space therebetween. The pressure thus increased would cause 45 the abutting cloth sections to spread or shift laterally, leaving gaps therebetween which in turn left unpolished or unground areas on the flat work-piece. These unpolished or unground areas appear as longitudinal streaks.

Thus, such prior construction only enables contact pressure to a degree much less than desired, and the roll itself has a minimum depth of resiliency which means that it is easily damaged or marked.

In marked contrast is my invention, whereby I obtain not only the maximum depth of resiliency under any desired contact pressure, but also a practical compressive and elastic surface.

5 Regardless of the contact pressure, which can be raised to any degree desired, there is no shifting or spreading of the circular sections and therefore no gaps to cause unpolished or unground areas or streaks. This is accomplished by cutting 10 the sections in such manner that their abutting surfaces are inclined to the shaft on which they are assembled. Such an angle of inclination can be approximately 15 degrees, but this may, if desired, be varied, as the greater the angle of inclination the greater the possible pressure which may be utilized. Such sections so inclined and assembled are preferably of a solid section of a somewhat elastic material, such as cork. They can also be made of hard rubber, but in any case 15 it is of prime importance that they be sufficiently resilient to provide a good compressive surface together with the maximum depth of resiliency.

The inclined abutting sections present at no time any permanent line contact which eliminates 20 the necessity of purposely oscillating the central shaft as heretofore necessary. A roll made up of such circular sections can either support an endless abrasive belt or its outer surface be supplied with an abradant surface and used directly 25 against the work-piece. In either case it presents an abrading surface which will readily yield to irregularities on the surface of the work-piece without permanently affecting the surface or hardness of the roll.

30 35 The elimination of marking the roll not only

increases its life but also allows changing from narrower to wider widths of work-piece without redressing or resurfacing the roll.

While I have shown and described one specific embodiment of my invention, I do not wish 5 to be limited exactly thereto, since various modifications may be made without departing from the scope of my invention, as defined in the following claim.

I claim:

A cylindrical roll for polishing or grinding substantially flat surfaces comprising a rotatable shaft, a plurality of flat-sided abutting resilient circular sections assembled on said shaft, the abutting surfaces of said flat-sided sections being 15 inclined at an angle to a line which is perpendicular with the axis of the roll, a wedge-shaped retaining section at each end of said assembled flat-sided sections, each of said wedge-shaped retaining sections having an angularly inclined inner surface for abutting the outer surfaces of the flat-sided sections at the ends of the assembly 20 which they abut, the diameter of said wedge-shaped retaining sections being substantially that of the flat-sided sections at the ends of the assembly 25 which they abut, the outer surface of said wedge-shaped retaining sections being substantially perpendicular to the line of contact of the roll, a relatively thin plate of smaller diameter disposed on either side of each of said flat-sided sections, 30 and means for securing said flat-sided sections, said wedge-shaped retaining sections, and said plates to said rotatable shaft.
